(57) **CLAIM**

What is claimed is the ornamental design for an electronic hub with opening data port, as shown and described.

DESCRIPTION

FIG. 1 is a top, rear, left perspective view of an electronic hub with opening data port shown in a closed position;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, rear, right perspective view thereof;

FIG. 9 is a top, front, right perspective view of the electronic hub with opening data port shown in an open position;

FIG. 10 is a top, rear, left perspective view of the electronic hub with opening data port shown in the open position;

FIG. 11 is a top, rear, right perspective view of the electronic hub with opening data port shown in the open position;

FIG. 12 is a rear elevational view of the electronic hub with opening data port shown in the open position;

FIG. 13 is a front elevational view of the electronic hub with opening data port shown in the open position;

FIG. 14 is a left side elevational view of the electronic hub with opening data port shown in the open position; and,

FIG. 15 is a right side elevational view of the electronic hub with opening data port shown in the open position.

Wherein the broken lines are for illustrative purposes only and form no part of the claimed design.
